UNITED STATES PATENT OFFICE.

MARTIN LANDENBERGER, OF PHILADELPHIA, PENNSYLVANIA.

DESIGN FOR A CAPE.

Specification forming part of Design No. 6,869, dated September 2, 1873; application filed May 8, 1873.
[Term of Patent 3½ years.]

To all whom it may concern:

Be it known that I, MARTIN LANDENBERGER, of Philadelphia, Pennsylvania, have invented a Design for a Garment, of which the following is a specification:

In the accompanying drawing, Figure 1 is a view of a circular garment embodying my design; Figs. 2, 3, and 4, views representing patterns of fabric which may be used.

The garment is semicircular, with a V-shaped notch in the center of the outer edge and a curved recess in the center of the straight edge. The garment is ornamented by parallel stripes *a b*, arranged as shown, and consisting of any minor arrangement of colors or shades so as to produce the effect of alternate light

and dark stripes, as in Figs. 2, 3, and 4. At the center of the garment is a hood having a central row of buttons and ornamented by alternate light and dark stripes, some parallel to the stripes *a b* and others being inclined, as represented.

I claim—

The design for a circular garment, as represented in and by the accompanying drawing.

In testimony whereof I have signed my name to this specification in the presence of two subscribing witnesses.

MARTIN LANDENBERGER.

Witnesses:

WM. A. STEEL,
HUBERT HOWSON.
